(57) **CLAIM**

The ornamental design for a bike tree rack, as shown and described.

DESCRIPTION

FIG. 1 is front perspective view of an implementation of a bike tree rack;

FIG. 2 is a front view thereof;

FIG. 3 is a rear view thereof;

FIG. 4 is a left view thereof;

FIG. 5 is a right view thereof;

FIG. 6 is a top view thereof;

FIG. 7 is bottom view thereof;

FIG. 8 is front perspective view of another implementation of a bike tree rack;

FIG. 9 is a front view thereof;

FIG. 10 is a rear view thereof;

FIG. 11 is right view thereof;

FIG. 12 is a left view thereof;

FIG. 13 is a top view thereof;

FIG. 14 is a bottom view thereof;

1 Claim, 9 Drawing Sheets
